UNITED STATES PATENT OFFICE.

EDWIN N. PREEBLE, OF BEVERLY, MASSACHUSETTS, ASSIGNEE TO UNITED SHOE MACHINERY COMPANY, OF PATERSON, NEW JERSEY, A CORPORATION OF NEW JERSEY.

SOLE-PRESSING MACHINE.

1,108,472.

Specification of Letters Patent. Patented Aug. 25, 1914.

Application filed February 1, 1912. Serial No. 674,686.

To all whom it may concern:

Be it known that I, EDWIN N. PREEBLE, a citizen of the United States, residing at Beverly, in the county of Essex and State 5 of Massachusetts, have invented certain new and useful Improvements in Sole-Pressing Machines; and I do hereby declare the following to be a full, clear, and exact description of the invention such as will enable 10 others skilled in the art to which it appertains to make and use the same.

The present invention relates to sole pressing machines, and more particularly to machines of this type which comprise a 15 shoe supporting jack and a coöperating sole pressing form having provision for a relative movement to place the sole of the shoe under pressure.

It is essential to the success of the leveling operation that the pressure exerted to level the sole be regulated in accordance with the varying requirements due to differences in the size, texture and quality of the soles. In order to obtain this regulation 25 easily and accurately, it is desirable to provide a manually controlled mechanism which is conveniently accessible to the operator and which may be manipulated without difficulty to adjust the degree of pressure upon the sole. The efficiency of the machine is further increased if some means are provided for measuring the amount of pressure employed in different cases in order 30 that the machine may be quickly and easily 35 adjusted to meet these conditions as they occur.

The object of the present invention is to provide a simple and efficient mechanism which is conveniently accessible to the operator and which may be manipulated to regulate the pressure and to automatically register the amount of pressure which is applied to the sole.

With this object in view, the several features of the invention consist in certain novel features of construction, combinations and arrangements of parts hereinafter described and claimed, the advantages of which will be obvious to those skilled in the 45 art from the following description.

In the accompanying drawings illustrating the preferred form of the invention; Figure 1 represents a side elevation of a sole pressing machine embodying the several features of the invention in their pre-

ferred forms; Fig. 2 is a detail showing upon an enlarged scale a partial front elevation of the sole pressing machine illustrated in Fig. 1; Fig. 3 is a section taken upon the line 3—3 of Fig. 2 looking in the 60 direction of the arrows; Fig. 4 is a detail showing a plan view partly in section of the indicating mechanism for registering the pressure exerted upon the sole.

The machine shown in the illustrated embodiment of the invention is provided with a shoe supporting last indicated at 1 and a coöperating sole pressing form indicated at 2. The last 1 is secured to a horizontal slide 3 which reciprocates in guideways formed in a table 4. The slide 3 is reciprocated on the table 4 to move the jack from a position of presentation at the front of the machine to a position of clearance directly beneath the sole pressing form and to return the jack 65 to its initial position after the pressing operation. The proper movements are imparted to the slide by a lever 5 pivoted at its lower end to a bracket 6 secured to the machine frame and connected at its upper end 70 to the jack through a link 7. The lever 5 is oscillated by a latch rod 8 provided with a slot 9 in the forward end arranged to engage a laterally projecting stud upon the lever and pivotally connected at its rear end 75 to a lever 10 pivoted upon the frame of the machine, and arranged to be actuated by a path cam secured to a cam shaft 11. The table 4 is supported in vertical guideways 80 formed in the frame of the machine and the requisite amount of pressure to level the sole 85 of the shoe is produced by an upward movement of the table when the last is positioned beneath its coöperating form. The table 4 is actuated automatically during the operation 90 of the machine by mechanism comprising a toggle lever 16 and a link 17 connecting the toggle with a cam secured to the shaft 11.

In order to insure the application of a 100 constant pressure upon the sole independently of the thickness of the sole, the form 2 is supported upon a cross head 18, and mechanism is provided for permitting the cross head to be depressed until the form 105 is seated upon the sole of the shoe and for locking the cross head in position during the pressing movement of the table 4. The form 2 is removably secured to a form carrier 20 and has provision for a slight rock- 110

ing movement relative thereto. The cross head is permitted to descend and seat the form and is raised at the completion of the pressing operation by a lever 21 pivoted to the frame at its lower end and connected to the cross head by a link 23. The lever 21 is provided with a cam roll 22 which engages with a rotary cam mounted upon the cam shaft 11. In order to lock the cross head in position during the pressing operation, a locking cam 25 is secured to a rock shaft 26 journaled in the frame of the machine above the form and is arranged to be swung inwardly over the cross head until it engages therewith and to be swung outwardly to allow the cross head to be raised. The cam 25 is swung inwardly by a suitable spring (not shown) and is positively forced out of engagement with the cross head by a lever 27 provided with a cam roll engaging with a cam on the shaft 11 and connected to the rock shaft through a link 28 and a rocker arm 29.

The above construction has been only briefly described herein as it is substantially the same as the construction shown and described in the patent to Mayo, No. 881,478, March 10, 1908. With this type of machine as at present constructed the operator is unable to determine the exact amount of pressure which is exerted upon the shoe and lasts are frequently broken owing to the excessive pressure which is employed. In accordance with the present invention, the pressure exerted upon various classes of soles is regulated by a simple and compact adjusting mechanism and means are provided for indicating or registering the amount of pressure, thus enabling the machine to be readily adjusted to the most efficient position without danger of breaking the lasts.

The requisite pressure is obtained by the use of a compression spring 35 received in a recess in the cross head 18 and interposed between the cross head and the form carrier 20, as shown clearly in Fig. 3. The spring is placed under any desired compression by an adjusting member 36 which passes loosely through the top of the cross head and is threaded into the form carrier at its lower end. In order to prevent a relative rotation of the adjusting member and form carrier a lug 33 is formed upon the carrier and a locking pin 34 is driven through the lug 33 and member 36. The upper end of the member 36 threadedly engages with a bevel gear 37 journaled in a bracket 32 and provided with a collar 24 which normally bears against the upper face of the cross head. The member 36 and form carrier 20 are adjusted relative to the cross head 18 by rotating the bevel gear 37 through an intermeshing bevel 38 which is secured to an adjusting shaft 39 provided

upon its outer end with a hand wheel 40. The total pressure which is exerted upon the sole is registered by an indicator mechanism comprising a spiral gear 41 secured to the shaft 39 and meshing with a spiral gear 42 secured to an indicator shaft 43. The indicator shaft 43 is journaled in a slotted arm 44 formed upon the bracket 32 and provided with a series of indicating characters upon its front face. A traveler 45 having an indicating finger is threadedly connected to the indicator shaft and is arranged to move longitudinally and give the proper indications as the shaft 43 is rotated. In order to allow for a slight compression of the spring 35 when the sole is put under pressure the bracket 32 is secured to the cross head 18 by bolt and slot connections indicated at 46. Thus in operation the adjusting member 36 and the bracket 32 together with the parts carried thereby are moved bodily with relation to the cross head when the machine is put under pressure. In order to manipulate the adjusting mechanism readily the machine is put under pressure compressing the spring 35 and raising the collar 24 and gear 37 from bearing upon the upper face of the cross head 18. This allows the gear to be rotated easily upon the upper end of the adjusting bolt 36 and regulate the initial compression of the spring 35.

While it is preferred to employ the specific construction and arrangement of parts shown and described, it will be understood that this construction and arrangement is not essential except so far as specified in the claims and may be changed or modified without departing from the broader features of the invention.

What is claimed is:—

1. A sole pressing machine having, in combination, a sole pressing form, a shoe supporting jack, means for relatively actuating the jack and form to exert pressure upon the sole of a shoe, means for regulating the pressure, and means for indicating the total pressure which is exerted upon the sole, substantially as described.

2. A sole pressing machine having, in combination, a shoe supporting jack, a sole pressing form, means for relatively actuating the jack and form, a spring for imparting the desired pressure to the form, means for adjusting the compression of the spring, and means for indicating the pressure exerted upon the sole of a shoe, substantially as described.

3. A sole pressing machine having, in combination, a shoe supporting jack, a sole pressing form, means for relatively actuating the jack and form, a spring for imparting the desired pressure to the form, adjusting mechanism for regulating the compression of the spring, and an indicator actuated

by the adjusting mechanism and arranged to register the pressure exerted upon the sole, substantially as described.

4. A sole pressing machine having, in combination, a shoe supporting jack, a sole pressing form, means for relatively actuating the jack and form, a spring for imparting the desired pressure to the form, an adjusting shaft, connections between the adjusting shaft and spring, an indicator shaft having an indicating member connected thereto, and connections between the two shafts, substantially as described.

5. A sole pressing machine having, in combination, a shoe supporting jack, a sole pressing form, means for relatively actuating the jack and form, a form carrier, a cross head, a spring interposed between the cross head and form carrier, an adjusting member rigidly connected to the form carrier at its lower end, a gear threadedly mounted upon the upper end of the adjusting member, and means for rotating the gear to adjust the form carrier with relation to the cross head and vary the initial compression of the spring, substantially as described.

6. A sole pressing machine comprising a sole pressing form, a form carrier, a cross

head, a compression spring interposed between the form carrier and cross head, an adjusting member rigidly connected to the form carrier, mechanism for actuating the adjusting member and a bracket supporting the mechanism and arranged to move relatively to the cross head when the sole is placed under pressure, substantially as described.

7. A sole pressing machine having, in combination, a shoe supporting jack, a sole pressing form, a form carrier, a cross head, a spring interposed between the two, an adjusting rod secured to the form carrier and passing loosely through the cross head, a bevel gear threaded upon the upper end of the rod for adjusting the rod, an adjusting shaft provided with a bevel gear meshing with the first mentioned bevel gear, an indicator shaft, gearing connecting said shaft to the adjusting shaft, and an indicating finger actuated by the indicator shaft, substantially as described.
